DIRECTION SIGNAL

Nelse Eskilson and Oscar Brander, San Pedro,
Calif.

Application March 26, 1936, Serial No. 71,028

3 Claims. (Cl. 116—54)

This invention relates to certain new and useful improvements in direction signals.

The primary object of the invention is to provide a direction signal for motor vehicles in which a signal arm that normally depends from a bracket mounting exteriorly of the vehicle body is adapted to be raised to an operative signalling position by devices manually operable at a point within the vehicle with the arm illuminated when moved into signalling position.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a side elevational view of a direction signal constructed in accordance with the present invention, a side wall of a motor vehicle body being shown in section and the signal arm at the outer side thereof illustrated by dotted lines in its elevated signalling position;

Figure 2 is a fragmentary side elevational view, partly broken away and shown in section of the direction signal and showing the manually operable cable for effecting a movement of the signalling arm;

Figure 3 is a vertical cross-sectional view taken on line 3—3 of Figure 2, showing the mounting for the signal arm;

Figure 4 is a vertical sectional view taken on line 4—4 of Figure 2, showing the operating means for the cable associated with the signal arm;

Figure 5 is a cross-sectional view of the signal arm, and Figure 6 is a diagrammatic view of a circuit for the signal light.

Referring more in detail to the accompanying drawing, the reference character 10 designates a side wall or other part of a motor vehicle upon which the direction signal is supported, the latter comprising a casing 11 attached to the outer side of the wall 10 with a signal arm 12 normally depending from the casing 11 when in inoperative position as shown in Figure 1, while a casing 13 secured to the inner side of the wall 10 in line with the outer casing 11 contains manually operable mechanism for effecting a movement of the signal arm 12, such as for instance the elevated signalling position illustrated by dotted lines 12a in Figure 1. The two casings 11 and 13 are secured to the wall 10 by tie rods or bolts 14 shown in Figure 2, and a spacer block 15 is interposed be-

tween the wall 10 and inner casing 13 as illustrated.

The outer casing 11 with which the signal arm 12 is associated is shown more clearly in Figures 2 and 3 and has a hollow bearing 16 journalled in the side walls 17 thereof, the inner angle end 18 of a rod 19 extending into the bearing 16 while the signal arm 12 is attached to the outer end of the rod 19. An insulation sleeve 20 is interposed between the bearing 16 and angle end 18 of the rod 19.

A drum 21 is fixed to the bearing 16 adjacent a side wall 17 of the casing 11 and said drum has a circumferentially extending groove for tracking reception of a cable 22 that has one end thereof anchored to the drum 21 at the point 23, the cable 22 extending through registering openings 24 in the wall 10 and spacer block 15 to enter the casing 13 at the inner side of the wall 10 for attachment to operating means therefor. An arcuate spring contact 25 extends partly around the bearing 16 in spaced relation to the drum 21 and is supported on the adjacent side wall 17 of the casing 11 by means of the insulation block 26. A contact pin 27 that is associated with the arcuate contact 25 extends radially of the bearing 16, insulation sleeve 20 and end 18 of the rod 19 and as shown in Figure 2 is insulated from said part, the contact pin 27 constituting a key connecting the bearing 16 and rod 19 for unitary rotation of the parts. When the contact pin 27 is spaced from the adjacent free end of the arcuate contact 25, the signal arm 12 is in its depending inoperative position and to retain the parts so disposed against accidental movement, a peripheral boss 28 carried by the drum 21 is engaged by the spring 29 as shown in Figure 2. As shown in Figure 6, the signal lamp 44 in the signal arm 12 is in an electric circuit with a source of energy, such as a battery 52, a wire 51 from one terminal thereof extending to the lamp 44 and from said lamp a wire 50 extends to the arcuate contact 25. A wire 53 extends from the other terminal of the battery and has an extensible circuit wire connection 54 with the contact pin 27. As shown in Fig. 3, one of the side walls 17 of the casing 11 is removable from the casing, and in assembling the parts in the casing 11, the said side wall is removed and the bearing 16, arm end 18 and drum 21 together with other associated parts are assembled on the side wall and the latter thereafter secured to the casing 11. The opposite end of the bearing 16 is suitably journalled and retained in the fixed side wall of the casing 11.

55

The operating means for the drum 21 is located within the casing 13 at the inner side of the wall 10 and as shown in Figures 2 and 4, a longitudinally fluted or corrugated shaft 30 is journaled in the side walls 31 of the casing 13. A drum 32 is keyed to the shaft 30 and has a ratchet disk 33 secured to one side thereof as at 34, the ratchet disk also being secured to the shaft 30 as illustrated. The cable 22 forms an operative connection between the two drums 21 and 32, the end of the cable 22 entering the casing 13 tracking in a peripheral groove in the drum 32 and having the end thereof anchored as at 35 to the drum 32. To cause the two drums to rotate comparatively slowly and in the absence of vibratory movement, a tensioned fibrous brake shoe 36 depending from the upper wall of the casing 13 is frictionally engaged with the peripheral wall of the drum 32 as clearly shown in Figure 4.

Manual rotation of the drum 32 is communicated to the drum 21 and signal arm 12 by means of the cable 22, the drum 32 being rotated by means of the handle 37 keyed to one projecting end of the shaft 30 as shown in Figure 4, the signal arm 12 being retained in its elevated signalling position as shown by dotted lines in Figure 1 by means of a pawl 38 pivoted as at 39 in the casing 13 with one end thereof engaged with the ratchet teeth 33a carried by the ratchet disk 33, the pawl being manually released from the ratchet disk by means of the handle carried thereby and extending outwardly of the casing 13 through the opening 41 in the bottom wall of the casing.

The signal arm 12 is of a spear head type as shown in Figs. 1 and 5 and includes a cylindrical glass casing 42 with arcuate translucent colored sheets or strips 43 arranged interiorly thereof at the front and rear sides of the signal arm for signalling purposes, one of the sheets 43 being preferably red and the other one amber colored. The illumination of the lamp bulb 44 in the signal arm is controlled by contacts 25 and 27.

From the above detailed description of the invention, it is believed that the construction and operation thereof will at once be apparent, it being noted that the signal arm 12 normally occupies the depending position illustrated in Figure 1 with the lamp 44 extinguished therein. When it is desired to operate the signal arm, the handle 37 at the inner side of the vehicle wall 10 is operated for rotating the drum 32 with such motion communicated to the drum 21 in casing 11 by means of the cable 22 for the elevation of the signal arm, the latter being retained in signalling position by the pawl and ratchet mechanism comprising the ratchet disk 33 and pawl 38. To lower the signal arm 12 to its inoperative position, the handle 40 is moved to release the pawl 38 from the teeth 33a of the ratchet disk 33 and the weight of the signal arm 12 causes downward pivotal movement thereof and such movement is

steadied by the brake shoe 36 frictionally engaged with the drum 32. The signal arm 12 is retained in its inoperative position against vibratory movement by the spring and boss arrangement 28 and 29 associated with the drum 21. Elevation of the signal arm 12 to operative position as shown by dotted lines at 12a in Figure 1, causes engagement of the contacts 25 and 27 and the illumination of the lamp 44 in the signal arm.

While there is herein shown and described the preferred embodiment of the invention, it is nevertheless to be understood that minor changes may be made therein without departing from the spirit and scope of the invention as claimed.

We claim:—

1. In a direction signal for automobiles, inner and outer horizontally aligned casings mounted respectively on the inner and outer sides of a wall of an automobile, a signal arm pivotally mounted in the outer casing, a drum in each casing, a cable connection between the drums, manually operable means for the signal arm attached to the drum in the inner casing, a ratchet disk rotatable with the drum in the inner casing, and a pawl engaged with the ratchet disk and extending outwardly of the casing for manual release from the ratchet disk.

2. In a direction signal for automobiles, inner and outer horizontally aligned casings mounted respectively on the inner and outer sides of a wall of an automobile, a signal arm pivotally mounted in the outer casing, a drum in each casing, a cable connection between the drums, manually operable means for the signal arm attached to the drum in the inner casing, a ratchet disk rotatable with the drum in the inner casing, a pawl engaged with the ratchet disk and extending outwardly of the casing for manual release from the ratchet disk, and a tensioned friction shoe carried by the inner casing for engagement with the periphery of the drum in the inner casing.

3. In a direction signal for automobiles, inner and outer horizontally aligned casings mounted respectively on the inner and outer sides of a wall of an automobile, a signal arm pivotally mounted in the outer casing, a drum in each casing, a cable connection between the drums, manually operable means for the signal arm attached to the drum in the inner casing, a ratchet disk rotatable with the drum in the inner casing and a pawl engaged with the ratchet disk and extending outwardly of the casing for manual release from the ratchet disk, and means for holding the signal arm against vibratory movements when in its inoperative position including a boss on the periphery of the drum in the outer casing and a spring arm carried by the casing for engagement with the boss.

NELSE ESKILSON.
